(57) **CLAIM**

The ornamental design for a plant stand, as shown and described.

DESCRIPTION

FIG. 1 is a perspective view of a plant stand showing my new design;

FIG. 2 is a left elevation view thereof;

FIG. 3 is a front elevation view thereof;

FIG. 4 is a right-side elevation view thereof;

FIG. 5 is a top plan view thereof; and,

FIG. 6 is a bottom plan view thereof.

The dotted lines illustrate portions of the plant stand that form no part of the claimed design.
